UNITED STATES PATENT OFFICE.

JOSEPH B. STRAUSS, OF CHICAGO, ILLINOIS.

WINDOW, &c.

1,021,492.

Specification of Letters Patent. Patented Mar. 26, 1912.

Application filed April 18, 1910. Serial No. 556,095.

To all whom it may concern:

Be it known that I, JOSEPH B. STRAUSS, a citizen of the United States, residing at Chicago, in the county of Cook and State 5 of Illinois, have invented a certain new and useful Improvement in Windows, &c., of which the following is a specification.

This invention relates to improvements in windows, etc., and has for its object to 10 provide a new and improved device of this description.

The invention is illustrated in the accompanying drawings, wherein—

Figure 1 is a view of a window embodying 15 the invention; Fig. 2 is a sectional view taken on line 2—2 of Fig. 1; Fig. 3 is a view of a portion of the frame; Fig. 4 is a sectional view taken on line 4—4 of Fig. 3; Fig. 5 is a sectional view showing a modified construction.

Like numerals refer to like parts throughout the several figures.

This invention has among other objects to provide a window which will be under perfect control, which can be easily and quickly installed, and wherein the sashes or elements balance each other, and which will not easily get out of order when in practical use.

In Fig. 1 there is illustrated a window arranged so that it may be opened either at the center or at the top and bottom. In this construction I prefer to provide a frame of suitable size and form. This frame is provided with two side frame pieces, each 35 consisting of two inclosing parts, 1, 2. Mounted between the inclosing parts at each side of the window is a pinion 3. Engaging on opposite sides of each pinion 3 are the racks 4, 5. The rack 4 is connected with 40 the moving sash or section 6, and the rack 5 with the moving sash or section 7.

As herein shown the racks 4 and 5 are made of angle irons, one of the angles of each rack being provided with teeth for engaging the pinion, the other angle projecting through a slot 8 between the bent edges 9 of the part 1 and the edges of the part 2, and are fastened to the sashes in any desired manner. It will be noted that the 50 part 1 is of channel shape and may be a channel-iron, and that the part 2 which may be also a metal plate, is located within the part 1 and is of less width than the said part.

There is preferably provided friction-reducing devices such as the rollers 10 which,

as shown in the drawing, are located between one angle of the rack and the bent edges 9 of the part 1. One or more separated pieces 11 are interposed between the parts 1 and 2 so as to keep them properly separated to permit the free movement of the racks as the sashes are raised and lowered. The pinions 3 are preferably movably connected in position so that they can be removed and renewed when they become worn. Any desired construction for this purpose may be used. As herein shown the part 2 may be provided with the removable section 12 which is held in place in any desired manner, and which, when removed, gives access to the pinion. The pinion may be connected with this part 12 so as to be removed therewith. The pinions, therefore, can be removed without removing the sashes and without disconnecting the sashes from the racks. I prefer to provide holes 12^a in the part 2 in proper position so that a pin thrust in the hole will engage the teeth of the rack so as to hold the rack while the pinion is being removed and replaced and thus keep the sashes in their proper position.

In the construction shown in Fig. 1, there are provided receiving pockets 13 and 14 at the top and bottom to receive the sashes or sections when they are spread apart to open the window at its middle. The frame may be made up the entire length including the sashes and pockets and may be provided at the ends of the sashes with the cross pieces 15, 16. These frames may be made up in the shop and shipped or may be shipped to the place of use before being assembled. When it is desired to operate a number of windows from one point or from one window the pinions 3 of the various windows may be operatively connected together by means of pinions or gears 17 so that by taking hold of one sash all the sashes of a series can be simultaneously moved. When the racks are made from angle irons the ordinary angle iron may be used and the teeth punched on one angle thereof. It will thus be seen that if desired the entire frame may be made of metal so as to be fire-proof and so as to occupy a small space.

When a window such as that shown in Fig. 1 is assembled, it will be noted that the sashes are perfectly balanced, one balancing the other. If it is desired to open the window at the middle, the lower sash, for example, is moved down, the rack connection

simultaneously causes the upper sash to move up and when the sash is released the parts will stop, leaving a window opening of any desired size. If it is desired to open the window at the top and bottom, the lower sash may be moved up. This would produce a corresponding downward movement of the upper sash. The window can, therefore, be opened at the top or bottom or at the middle, and is under perfect control and completely balanced and responds to a slight pressure applied to either sash. This construction may be applied to windows or other devices where there are moving sections. It will be noted that the side frame pieces, as shown in Figs. 2 and 3, are made up of an outside channel, an inside plate, a pinion mounted between them, with racks between the channel and plate, each rack having a part projecting through the space between the channel and plate, the channel and plate rigidly connected together at intervals, and that the plate may be in one or several pieces as desired. It will further be noted that when these side frame pieces are connected together in any desired manner, as by cross pieces of any suitable shape, the frame is formed. The side pieces may be made up in the shop complete, so that the parts are properly held together and properly protected during shipment, and the frame can then be easily and quickly completed at the point of use. It will also be seen that these side frame pieces constitute a frame for guiding the movable sections, a support for the movable sections, operating mechanism therefor, a balancing device, and a weather protecting device. The side pieces are detachably connected. I prefer to detachably connect the parts 1 and 2 together. When the rollers 10 are omitted, the racks directly engage the part 9 of the channel 1.

I claim:

1. A device for windows, etc., comprising an outside channel with its flanges projecting toward the sash, an inside plate located on the same side of the web of the channel as the said flanges, an intermediate pinion, toothed racks between the channel and plate engaging said pinion, said racks having projecting parts which project through the space between the channel and plate, said inside plate engaging said racks and acting as a guide therefor, and means for connecting the channel and plate rigidly together.

2. A device for windows, etc., comprising a movable section and a rack connected therewith, a pinion engaging said rack, and two inclosing separated members between which said pinion and rack are mounted, both of said members wider than the pinion and inclosing the rack teeth between them.

3. A device for windows, etc., comprising side frame pieces each made up of two separated parts, a pinion mounted between said

parts, said parts wider than the diameter of the pinion and inclosing said pinion, racks between said parts and engaging the pinion, said racks having engaging portions which project between the edges of said parts.

4. A device for windows, etc., comprising a rack and pinion and an inclosing device therefor, consisting of two separated parts wider than the diameter of said pinion.

5. A device for windows, etc., comprising side frame pieces each made up of separated parts, a pinion removably mounted between said parts, both of said parts wider than the diameter of said pinion, racks engaging said pinion and means for removing said pinion while said separated parts are in position.

6. A device for windows, etc., comprising side frame pieces, each made up of separated parts, a pinion removably connected between said parts, racks engaging said pinion and means for directly engaging and holding said racks in position when the pinion is removed.

7. A device for windows, etc., comprising a side frame provided with a one-piece member bent up at its edges to form a trough, and a pinion located in said member between said bent edges, a plate located in said member between said bent edges and of less width than said member so as to leave open spaces between the edges of said plate and the bent edges of said member, a rack engaging said pinion, said rack having a part which engages the edge of said plate so as to be guided thereby, and which projects beyond said plate.

8. A device for windows, etc., comprising a side frame piece made up of an outside piece having a flat outside face, the edges thereof bent inwardly, an inside piece fastened to the outside piece so as to form an inclosed space between said pieces, a pinion located in said space, two racks within said space, each having a portion which engages said pinion, said inner piece overlapping the portions of both racks which engage the pinion.

9. A device for windows, etc., comprising a unit frame piece, made up of an outside inclosing piece and an inside inclosing piece, fastened together so as to leave a space between them, a pinion in said space, racks having toothed portions in said space and engaging said pinion, said outside and inside inclosing pieces engaging said racks so as to prevent their lateral movement.

10. A device for windows, etc., comprising a side frame piece, provided with an outside and an inside part, said outside and inside parts fastened together with a space between them, a pinion located in said space, racks consisting of angle pieces, one angle

of which is provided with teeth to engage the pinion, the other angle projecting from between said outside and inside parts, said inside part engaging the fillet of the angle 5 of said angle pieces so as to act as a guide therefor.

11. A device for windows, etc., comprising a frame having side pieces each provided with an outside and an inside part, 10 the outside part consisting of a one piece member bent up at its edges to form a trough, a pinion located in said member between said bent edges, racks engaging

said pinion and located between said parts, projecting portions connected with said 15 racks and projecting between said parts and beyond the inside part, the edges of said inside part forming guides for said projecting portions.

Signed at Chicago, Illinois, this 9th day 20 of April, 1910.

JOSEPH B. STRAUSS.
